ILLINOIS.

BLOWPIPE.

1,409,220.

Specification of Letters Patent. Patented Mar. 14, 1922.

Application filed March 29, 1919. Serial No. 286,074.

To all whom it may concern:

Be it known that we, WILLIAM J. LEIGHTY and ISAIAH ALLISON, citizens of the United States, and residents of Chicago and Downers Grove, respectively, in the county of Cook and State of Illinois, have invented certain new and useful Improvements in Blowpipes, of which the following is a description, reference being had to the accompanying drawing, which forms a part of our specification.

Our invention relates more particularly to an oxy-acetylene blowpipe adapted for use either as a cutting blowpipe or as a welding blowpipe, by the mere substitution or interchange of the tips or nozzles; such interchange being readily accomplished and gas-tight connections provided because of the simple construction and arrangement.

Another object of our invention is to provide a blowpipe with a mixing chamber of the injector type located at a point as far removed from the flame as possible; that is to say, a mixing chamber located in the rear end of the handle of the torch, whereby a normal or neutral mixture of the combustible gases is ensured, regardless of the length or duration of time of continuous welding or cutting operation of the torch.

A further object of our invention is to provide means whereby the combustible mixture of gases will be kept cool and therefore protected from the heat of the flame while said gases are traveling from the mixing chamber in the handle portion of the blowpipe to the delivery end or tip of the nozzle.

A further object of our invention is to provide a blowpipe having a head provided with a plurality of passages and adapted to receive a cutting tip or nozzle whereby a multi-jetted pre-heating flame is provided about a single jet of oxygen when the blowpipe is intended for cutting purposes; said tip being readily removable and easily replaced by a tip constructed so as to effectually close the passage in the head for the oxygen and thus provide a neutral welding flame that will be positively maintained, regardless of whether the valve which controls the oxygen passage in the blowpipe is fluid or gas-tight.

Another object of our invention is to provide a blowpipe simple in construction and design, light in weight, economical in manufacture and which may be readily repaired; at the same time a blowpipe possessing a

wide range of usefulness. The above enumerated advantages, as well as others inherent in the construction, together with the objects of the invention, will be more readily comprehended from the following detailed description of the accompanying drawing wherein:

Figure 1 is a longitudinal detail sectional view of our improved blowpipe provided with a cutting tip or nozzle; the view being taken substantially on the line A—A of Figure 2 and looking in the direction of the arrows.

Figure 2 is a transverse sectional view taken on the line B—B of Figure 1 looking in the direction of the arrows and disclosing the oxygen inlet or admission valve and inlet stem.

Figure 3 is a transverse sectional view taken on the line C—C of Figure 1 looking in the direction of the arrows and disclosing the acetylene or hydrogen admission valve and inlet stem.

Figure 4 is a partial longitudinal sectional view of the rear or handle end of the blowpipe, taken substantially on the same line as Figure 1 and disclosing the cutting gas-control valve in open position.

Figure 5 is a transverse sectional view taken on the line D—D of Figure 1 to more clearly disclose the arrangement of gas passages in the cutting tip or nozzle.

Figure 6 is a longitudinal sectional view of the nozzle or tip end of the blowpipe, taken substantially on the same line as Figure 1 and showing the blowpipe provided with a welding tip substituted for the cutting tip disclosed in Figure 1.

The exemplification disclosed in the drawing, we believe to be the simplest and best adaptation of the invention; but we do not wish to be understood as limiting ourselves to the exact construction disclosed, as the invention may have expression in somewhat different mechanical form without departing from the spirit of the invention. In the specific mechanical expression of the invention, as disclosed in the drawing, the blowpipe comprises a main or body portion 10, which may be in the nature of a suitable casting provided with passages as herein-after described and also adapted to receive an outer shell or cover as at 11. The rear end of the body portion or casting 10 is provided with a pair of valve-stems or ex-

tensions 12 and 13, projecting in a suitable angular manner from the rear end of the main or body portion 10 and preferably formed integral therewith; and each valve-
5 stem or extension 12 and 13 is provided with a suitable inlet stem as at 14 in Figure 1 and at 15 in Figure 2, adapted to receive the end of a hose or conduit leading to the respective gas-supplies; that is, the stem 14 is adapted
10 to be connected with a suitable supply of oxygen while the stem 15 is adapted to be connected with a suitable supply of acetylene or hydrogen. The valve-stem 12 is provided with a suitable needle-valve as at 16, see Fig-
15 ure 2, controlled by a suitable hand-wheel 17; the valve 16 being threaded in the valve-
stem 12, as shown in Figure 2 and a gas-
tight connection being effected by means of a suitable packing-nut 18 shown threaded
20 onto the exterior of stem 12, whereby a packing-gland 19 is forced into intimate relation with the end of the stem 12 and about the valve 16. The stem 12 is provided with a gas-passage 20 which connects with a gas-
25 chamber 21 formed in the rear end of the body portion or casting 10, see Figure 1; the chamber 21 being closed by means of the closure member or cap 22 which is shown threaded into the interior of the casting 10
30 and provided with a flange adapted to overlap and abut the end of the casting as shown at 23 so as to effect a gas-tight connection; the closure member or cap 22 being also shown provided with a wrench-receiving
35 portion or surface at 24 whereby the closure member or cap may be screwed into or out of place.

The body portion or casting 10 is provided with passages disposed in a longitudinal
40 manner; and the rear end of one of said longitudinal passages is threaded to receive an injector-tube 25 which communicates with the gas-chamber 21. The inner end of the injector-tube 25 is shown threaded to receive one end of a combining tube or throat 26 which is apertured and constructed to provide a chamber or space about the immediate tip of injector-tube 25. The end of the passage in the main or body portion 10, at a
45 distance removed from the threaded end which receives the injector-tube 25, is somewhat enlarged to provide an annular chamber 27.

The side walls of the combining tube or
50 throat 26, at a point coincident with the tip of injector 25 is provided with ports 28 whereby communication is established between the annular chamber 27 and the passage through the combining tube or throat 26; which passage communicates with the mixing chamber or passage 29 leading toward the opposite end of the main or body portion 10. The opposite end of mixing chamber or passage 29 is provided with a
55 conduit or tube 30 shown screwed into place,

while the opposite end of conduit or tube 30 is screwed into a suitable socket or opening in the head 31 which is provided with a passage 32 which communicates with a suitable annular passage or chamber 33. The chamber 33 is formed in head 31 so as to be disposed at the inner end of the tip or nozzle 34. The tip 34 is provided with a plurality of passages 35 which communicate with chamber 33 and terminate at the outer end 75 of the tip 34 in more or less restricted orifices as shown in Figure 5. The passages 35 (of which there are a suitable number) are circumferentially disposed about a central passage 36 formed in the tip or nozzle 34. 80 The passage 36 at its inner end communicates with a passage 37 formed in the head 31 and the passage 37 communicates with one end of a conduit or tube 38 concentrically disposed about conduit or tube 30. The 85 other end of conduit 38 is suitably threaded into the main or body portion 10 and communicates with an annular space or chamber 39 formed in the body portion or casting 10, as shown in Figure 1; said chamber being 90 disposed about the upper or inner end of tube 30. The chamber 39 communicates with a longitudinally disposed passage 40 (shown in dotted lines in Figure 1 and in cross-section in Figure 3); and the rear end 95 of passage 40 communicates with a passage 41 which latter communicates with the annular chamber 42, see Figures 1 and 3.

The main body portion or casting 10 is longitudinally cored to receive a housing 100 43 which has communication by means of suitable ports 44 with the annular chamber 42. The valve-housing 43 is provided with a valve-stem 45, the upper end whereof is provided with a suitable valve 46 having a conical taper and adapted to seat on the valve-seat at the orifice of the chamber in valve-housing 43; namely at the end of the valve-housing which communicates with the gas-chamber 21. The valve-housing 110 43 has its inner end preferably threaded, as shown in Figure 1 and provided with a suitable nut 47 whereby the valve-housing 43 is firmly secured in position in the main or body portion 10; the nut 47 and outer 115 end of valve-housing 43 being shown beveled so as to form gas-tight connections with the casting 10, see Figure 1. The stem 45 of valve 46 is disposed through the valve-housing and is made fluid-tight by means 120 of a packing nut or sleeve 48, which receives the threaded end of the housing 43, and a suitable packing-gland 49; the latter being maintained under uniform pressure by means of a spring 50 disposed about the 125 stem 45 within the sleeve 48 and bearing against the wall of the nut 48. A suitable washer is preferably placed on the packing-gland 49 to receive the pressure of spring 50. This construction maintains a fluid- 130

tight relation between the packing-gland 49 and valve-stem 45.

The inner end of valve-stem 45 is preferably threaded in or otherwise suitably secured in a yoke guide member 51; while the portion of the stem 45 intermediate of nut 48 and yoke member 51 is provided with a suitable compression spring 52 disposed about the stem, with one end taking 10 against the end of nut 48, while the other end engages a nut 53 which is screwed onto the threaded end of valve-stem 45 and held in adjusted position by a suitable lock-nut, as at 54. With this construction it is evident 15 that proper pressure may at all times be exerted on the valve 46 so as to normally maintain the latter on its seat. The inner end of valve-stem 45, as previously stated, is preferably threaded into yoke member 51 20 and the latter is provided with a pin, as at 55, which will prevent a trigger 56 from flying forward when the latter is released. The yoke-member 51 is held loosely in a 25 guide-way formed in the main or body portion 10 by means of a block 57 which is secured in place by a pin 58.

The trigger 56 is pivotally secured at 59 in a suitable manner to the main or body portion 10 and passes through yoke-member 30 51 as well as through a suitable opening in the outer shell or casing 11; the pivot pin 59 being disposed transversely through the body portion and the outer shell or casing 11 to assist in maintaining the latter in 35 place. The trigger 56 is provided with a suitable latch 60 pivotally secured on the trigger about the pin 61; the latch-member 60 being controlled by means of a spring 62 which normally tends to force the free 40 end of latch-member 60 into engagement with the notches or teeth of a quadrant or locking member 63; the engagement of latch-member 60 with the teeth or quadrant 63 maintaining the trigger 56 in its 45 retracted or adjusted position. The trigger 56 is preferably protected by a suitable guard, as at 64.

The acetylene gas or hydrogen is brought 50 into the valve-stem or projection 13 and into the passage 65; its flow through passage 65 being controlled by needle-valve 66 shown threaded into the valve-stem 13, see Figure 3; with a gas-tight connection being formed by means of packing-gland 67 55 and a suitable nut 68. Upon proper operation of needle-valve 66, by means of hand-wheel 69, the combustible gas passes through passage 65 to the annular orifice or chamber 27 which is disposed about the mixing tube 60 or throat 26 and the inner end of injector 25. The acetylene or hydrogen is drawn 65 into the mixing tube or throat 26 through the apertures 28 and about the inner tip of injector 25 through the action of the inrushing oxygen passing from chamber 21, 70

through injector 25; and the two gases are then injected into the combining tube or throat 26 from whence they pass into the mixing-chamber 29. The mixed gases, as is evident from the previous description, 75 will then pass through conduit or tube 30 into passage 32 of head 31 and thence into annular chamber 33 and be discharged through the multiple of passages 35 disposed in a circumferential manner about 75 the central passage or outlet 36 of nozzle or tip 34. The discharging mixed gases provide the preheating flame when the cutting-tip or nozzle 34 is employed. The cutting flame or oxygen jet is produced by 80 opening valve 46. Valve 46 may be forced off its seat by a backward pull on trigger 56, which is thereby brought into engagement with guide-yoke 51 to which valve-stem 45 of valve 46 is secured. The backward pull of trigger 56 will cause the spring-actuated latch member 60 to engage with the teeth of the quadrant or holding member 63 and maintain the trigger, with the valve 46, in its adjusted position against 85 the action of spring 52. The opening of valve 46 as just described establishes communication between valve-housing 43 and the chamber 21 which is provided with oxygen, thus allowing the oxygen-gas to 90 pass into the valve-housing and through ports 44; into annular chamber 42 which communicates with passage 41, and by means of longitudinally disposed passage 40 (shown in dotted lines in Figure 1) is 100 conveyed into the annular chamber 39. The oxygen gas from chamber 39 is thence conveyed lengthwise of conduit 38 (and therefore about conduit 30 and acting as a cooling medium) to the passage 37 in the head 105 31 and thence into the centrally disposed passage 36 in the tip 34. The central portion of tip 34 has its upper or inner end slightly extended and beveled so as to provide a fluid-tight joint at 70 by reason of 110 the conical orifice provided for passage 37 in head 31. The cutting flame is provided with the valve 46 in the unseated condition shown in Figure 4; while the blowpipe will merely provide a preheating flame 115 when the valve 46 is in the position shown in Figure 1.

Fluid-tight connections between the conduits or tubes 30 and 38 with the main or body portion 10 are provided by proper 120 threaded joints made as shown in the drawing; while suitable gas-tight connection between tube or conduit 38 with the head 31 is also effected by means of a suitable silver soldered joint, as at 71.

Our improved blowpipe may be readily converted from a cutting blowpipe into a welding blowpipe by simply removing the tip or nozzle 34 and substituting the tip or nozzle 72 shown in Figure 6. The tip 72 130

is adapted to screw into the end of head 31 the same as tip 34 and has its inner central end provided with a suitable tapered socket for the reception of a conical plug 73, which 5 takes the place of the extended end of tip 34, previously described and is adapted to form gas-tight connection with the tapered or conical orifice of the passage 37 in the head 31, namely the passage which communicates with outer tube 38. The tip or nozzle 72 is provided with a single longitudinal passage 74 terminating at its inner end with the radial passages or ports 75, disposed about the plug 73 and which 10 communicate with the annular chamber 33 formed adjacent the tip-receiving end of head 31 and with which passage 32 communicates; the latter passage in turn communicating with the inner concentric tube 15 30 which receives the combustible mixture of acetylene and oxygen, or other suitable gases, from mixing chamber 29.

As is evident from the construction shown and described, aside from depending upon 25 valve 46 to prevent an improper discharge of oxygen into conduit or tube 38, the plug 73 will ensure against the passage of oxygen through passage 37 into the tip or nozzle 72; the plug 73 being firmly forced to 30 its seat by the proper screwing of tip 72 into place.

As is evident from the construction shown and described, especially when the blowpipe is used as a cutting blowpipe, the oxygen gas which is used for cutting purposes 35 is caused to travel lengthwise about the conduit containing the combustible mixture which provides the preheating flame. Causing the oxygen to travel about conduit 30 40 enables the oxygen gas to be employed as a cooling medium for the mixture passing through conduit 30.

It is also evident from the construction shown and described that the injector and 45 combining-tube or throat as well as the oxygen controlling valve, its housing and correlated parts, are readily accessible upon the removal of the closure member or cap 22; and, furthermore, a fluid-tight connection 50 for the valve-stem 45 is effected by the uniform pressure which may be exerted by spring 50, which is controlled and regulated by the positioning of nut 48 on the inner end of the valve-housing. Removing pivot 55 pin 59 will allow the trigger 56 to slip out of the yoke-guide 51 and at the same time permit the shell or cover 11 to be slid lengthwise of the conduit or tube 38 and thus enable any desired adjustment being made 60 of the packing or valve-stem.

It is, of course, understood that in the operation of the blowpipe as a cutting torch the metal is previously pre-heated to a sufficient degree by the flame caused by the combustible mixture, which passes through tube 65

30 and the plurality of ports or passages 35 in the tip 34; and that after said pre-heating the cutting flame is provided by a suitable operation or backward pull of trigger 56 so as to cause valve 46 to move off 71 its seat and permit a quantity of oxygen to flow past the valve 46 and through the communicating passages to outer tube or conduit 38 and thence through the central passage 36 of the tip or nozzle 34. In the construction shown and described, the combining and mixing chamber of the blowpipe is provided at a distance removed from the head or nozzle of the blowpipe, namely at a point where it is not apt to be affected by 71 the heat caused during the cutting or welding operation, with the result that a much more reliable and satisfactory blowpipe is produced.

Having described our invention what we 81 wish to claim is:—

1. A blowpipe of the class described, comprising a handle portion having gas passages and a gas-chamber at the rear end of said handle portion, an injector removably secured in the rear end of said handle portion intermediate of said gas-chamber and one of said passages, a valve-housing removably secured in said handle portion and arranged in communication with said chamber and a second gas passage, a spring-controlled normally seated valve arranged in said housing adapted to control the communication between said chamber and said passage, and pivoted means extending through to the handle exterior whereby said spring-controlled valve may be moved off its seat.

2. In a blowpipe of the class described, a handle portion provided with gas passages 10 therein and with a gas-chamber at the rear end thereof, means removably secured in the rear end of said handle portion whereby mixed gases will be conveyed into one of said gas passages, a valve-housing removably secured in the handle portion, a valve slidably mounted in the housing and normally maintained on its seat whereby communication between said chamber and a second gas passage is controlled, means, operable from the handle exterior, for moving said valve off its seat, and removable closure means for said gas chamber and the rear end of said handle portion.

3. In a blowpipe of the class described, the 120 combination of a handle portion comprising a casting having gas passages therein, a pair of concentrically arranged conduits or tubes connected at one end to said casting and each communicating with one of said passages, a 121 head provided with a plurality of passages and removably connected to the outer end of the concentric conduits, with each passage in the head communicating with a separate conduit, with a tip removably secured in said 130

head, and means disposed at the inner end of said tip whereby communication with one of the passages in said head may be closed off.

4. A blowpipe, comprising a handle portion, a nozzle or tip-receiving head, concentric gas-conveying tubes or conduits connecting said head to the handle-portion, the handle-portion consisting of a casting provided with a gas-chamber at the rear end and with 10 a mixing chamber disposed toward the other or forward end and arranged in communication with one of said tubes or conduits, a removable closure member for the rear end of the casting, a combined injector and combining tube disposed intermediate of said gas-chamber and the mixing chamber and removably secured in said casting, a valve-controlled passage intermediate of said gas-chamber and the second tube or outer conduit whereby a single gas is conveyed to said head independently of the mixed gases flowing from said mixing-chamber and made to travel lengthwise of the first mentioned or inner conduit to act as a cooling medium.

25 5. A blowpipe, comprising a handle portion provided with longitudinal passages and a chamber at the rear end thereof communicating with a gas supply, removable closure means for said rear end of the handle portion, a nozzle or tip-receiving head, concentric gas-conveying tubes or conduits intermediate of the longitudinal passages of the handle portion and said head, an injector removably secured in the rear end of said 30 handle portion intermediate of the chamber and one of the longitudinal passages and in communication therewith, a combining tube removably secured about the forward or tip end of the injector and provided with inlet 35 openings communicating with a second gas supply whereby a combined mixture is conveyed to the inner gas-conveying tube, a spring-controlled valve disposed intermediate of said chamber and a second longitudinal passage whereby a single gas is conveyed to the outer gas-conveying tube, and means whereby said valve may be forced off its seat.

6. A blowpipe of the class described, comprising a handle portion provided with a casting having gas passages and a gas chamber at the rear or outer end of the casting, a closure member for the rear end of the casting, one of said gas passages communicating with one gas supply while the chamber communicates with a second gas supply, a combined injector and combining tube removably secured in said casting at the rear end thereof, the injector communicating with said gas chamber while said combining tube communicates with the passage communicating with the gas supply, a spring-controlled valve intermediate of said gas chamber and a second gas passage, and a trigger whereby said spring-controlled valve may be actuated and a single gas permitted to flow from

said chamber through the second gas passage.

7. A blowpipe of the class described, comprising a handle portion consisting of a casting having gas passage and a gas chamber 70 at the outer end thereof, a removable closure member for the outer end of said casting to permit access to said chamber, said chamber having communication with one gas supply while one of said passages communicates 75 with a second gas supply, a tip-receiving head provided with a number of gas passages, a gas-conveying tube or conduit intermediate of one of the gas passages in the casting and one of the passages in said head, 80 a second conduit or tube arranged concentric with the first tube and disposed intermediate of a second passage in said casting and a second passage in said head, an injector removably secured in said casting intermediate of said chamber and one of said 85 passages, a tubular valve housing removably secured in the rear end of the casting intermediate of said chamber and the second gas passage, a normally seating valve slidably 90 mounted in said valve-housing, means adjustably secured to the inner end of said housing for maintaining a gas-tight relation between the housing and valve-stem disposed therethrough, and means operable 95 from the handle exterior whereby said valve may be forced off its seat and a single gas permitted to flow from the chamber to the second conduit.

8. A blowpipe of the class described, comprising a handle portion consisting of a casting having a pair of longitudinally disposed passages, a gas chamber at the rear end of the casting and ports or passages adapted to effect communication with the 100 rear ends of said longitudinally disposed passages, an injector and combining tube removably secured in the casting at the rear end of one of said longitudinally disposed passages, said injector and combining tube 105 being adapted to have communication with said chamber and with some of said ports or passages, respectively, a valve-housing removably secured in the rear end of one of said longitudinally disposed passages whereby communication between said gas chamber and said longitudinally disposed passage may be established for conveying a single 110 gas therethrough, a spring-controlled valve slidably mounted in said valve-housing for 115 normally closing off communication through said housing, adjustable means for effecting gas-tight relation between the housing and the stem of said valve at the inner end of the housing, and means operable from the 120 handle exterior for moving said valve against the action of its spring.

9. In a blowpipe of the class described, a handle portion provided with gas passages and a gas chamber at the rear end, a re- 125

movable closure member for said rear end to permit access to said chamber, an injector removably secured in the rear end of the handle portion intermediate of said chamber and one of said passages, said injector being removable through the rear end of the handle portion when said closure member has been removed, a valve-housing removably secured in the handle portion and arranged to have communication with said chamber and a second gas passage, a valve slidably mounted in said valve housing, means adjustably secured to the valve-stem whereby a regulable pressure on the valve may be exerted and the latter normally held on its seat, and a pivoted trigger extending to the handle exterior whereby said valve may be forced off its seat and a single gas permitted to flow from the gas chamber into the said second gas passage.

10. A blow-pipe of the class described, comprising a handle portion composed of a casting having gas passages and a gas chamber, an injector and combining tube removably secured in the rear end of the casting intermediate of the chamber and one of said gas passages, a spring-controlled valve for controlling the flow of gas from said gas chamber through a second gas passage, a pair of concentrically arranged conduits, one of which communicates with the gas passage communicating with the injector and combining tube, while the other conduit communicates with the passage controlled by said spring-controlled valve, a head secured to the outer ends of said conduits and having a plurality of passages separately communicating with said conduits, in combination with a removable tip or nozzle secured in said head, and means controlled by the positioning of the tip whereby one of the passages in said head may be closed.

11. A blow-pipe comprising a handle portion provided with valved inlets and gas passages, one of the passages constituting a mixing chamber and having communication with a valved inlet, a gas chamber formed at the rear or outer end of the handle portion, a cap removably secured to the rear end of the member and constituting a closure for said chamber, an injector removably secured intermediate of said chamber and said last mentioned passage and intermedi-

ate of the point of communication between said valved inlet and said passage, a second gas chamber adjacent the inner or forward end of the handle and arranged concentric with said gas passage, a second gas passage intermediate of the second gas chamber and the chamber at the rear end of the handle, a normally seated valve controlling communication between said second passage and the chamber at the rear end of the handle, and means whereby said last valve may be actuated and a single gas permitted to flow from the chamber at the rear end of the handle to the second mentioned gas chamber, in combination with a pair of concentric conduits, the inner one communicating with the first mentioned gas passage, while the outer one communicates with said second mentioned gas chamber.

12. A blow-pipe of the class described, comprising a handle portion composed of a casting having longitudinal gas passages and a gas chamber in the rear end thereof, a removable closure member for the rear end of said casting to permit access to said chamber, an injector and combining tube removably secured in the rear end of the casting intermediate of the gas chamber and one of said longitudinal passages, a tubular valve-housing removably secured in the rear end of the casting intermediate of the chamber and a second longitudinal passage, said housing having ports or openings arranged in communication with said second longitudinal passage, a valve slidably mounted in said housing and provided with a stem disposed through the inner end of the housing, means adjustably secured to the inner end of said housing for effecting gas-tight relation between the housing and said valve-stem, means adjustably secured to the end of the valve-stem whereby the valve is placed under regulable pressure, and a trigger pivotally secured in the handle portion and in operative relation with the valve-stem whereby said valve may be controlled from the handle exterior.
